FOOT THERAPY DEVICE

Leonard F. Rucker, Hollywood, Calif.

**Application January 18, 1932, Serial No. 587,200
Renewed July 28, 1934**

2 Claims. (Cl. 174—89)

This invention relates to improvements in therapeutic devices.

The general object of the invention is to provide an improved electrically operated device for treating the human foot.

Another object of the invention is to provide an improved device for stimulating the blood circulation in the foot and for strengthening the muscles of the foot.

10 A further object of the device is to provide novel means to induce a flow of electric current through each foot of a patient and including other means to induce a flow of current from one foot to the other.

15 Other objects and the advantages of this invention will be apparent from the following description taken in connection with the accompanying drawing, wherein:

Fig. 1 is a top plan view of my improved device.
Fig. 2 is an enlarged section taken on line 2—2.

Fig. 3 is an enlarged bottom plan view of the

Fig. 4 is a detail view of the same detail.

25 Fig. 4 is an enlarged fragmentary detail.
Referring to the drawing by reference characters I have indicated my improved therapeutic device generally at 10. As shown the device 10 comprises a housing 12 which includes end members 13 and 14, sides 15, a top plate 16 and a bottom 17. The various portions of the housing 12 are preferably made of an electrical insulating material such as wood, a fiber composition "Bakelite", etc.

35 Positioned on the top plate 16 I provide a pair of spaced foot plates 18 and 19 and a pair of spaced heel plates 20 and 21. These plates are made of an electrical conductive material and I preferably use zinc. The foot and heel plates may be secured to the top plate 16 in any desired 40 manner but in Fig. 4 I have shown the plate 18 as secured to the top 16 by a bolt 22 which is riveted to the plate 18, and which has a nut 23.

The plate 18 is provided with an electrical contact terminal 24, the plate 19 with a terminal 25, the plate 20 with a terminal 26 and the plate 21 with a terminal 27. The terminals 24, 25, 26 and 27 may be made similar to the securing bolts 22 and also serve to secure their associated plates to the top 16.

50 Within the housing 12 I provide a lamp casing 28 in which I provide an electric light bulb 29 mounted in a socket 30 which includes electric contact terminals 31 and 32. In the top plate 16 above the bulb 29 I provide an aperture 33 which is closed by a transparent plate 34.

Also within the housing 12 I provide a casing 35 in which I provide a rheostat 36, a fuse block 37 and a sliding switch 38.

The rheostat 36 includes an electric resistance coil 39 having one end thereof electrically connected to a terminal 40, a contact track 41 having a terminal 42 and a contact arm 43 which is secured to a shaft 44. The shaft 44 extends upward through the top 16 where it has secured thereto a knob 45 which is shown as including a pointer 46 which coacts with a graduated scale 47. 5 10

The fuse block 37 includes a fuse clip 48 having a terminal 49 thereon and a fuse clip 50 having a terminal 51 thereon. The fuse clips 48 and 50 are adapted to be electrically connected by a fuse 52 which may be of any desired type. 15

The switch 38 includes a plurality of positive contacts 53, 54, 55 and 56 and a plurality of negative contacts 57, 58, 59 and 60. The positive contacts are adapted to be electrically connected by a contact bar 61 and the negative contacts are adapted to be electrically connected by a contact bar 62.

The contact bars 61 and 62 are mounted on opposite sides of a block of electrical insulating material 64 having a handle 65 which extends upward through an aperture 66 in the top plate 16.

In one position of the block 64 the contact bar 61 electrically connects the positive contacts 53, 54 and 55 and the contact bar 62 electrically connects the negative contacts 57, 58 and 59.

In the other position of the block 64 the bar 61 electrically connects the positive contacts 53, 54 and 56 and the contact bar 62 electrically connects the negative contacts 57, 58 and 60. 35

The device is shown as adapted to be electrically connected to a suitable source of electrical energy by a contact plug 67 which is electrically connected to a positive wire 68 and a negative wire 69. The positive wire 68 is connected to the terminal 49 of the fuse clip 48 and the negative wire 69 is connected to the contact 57. A wire 70 connects the terminal 51 of the fuse clip 50 with the terminal 40 of the rheostat and a wire 71 connects the rheostat terminal 42 with the light socket terminal 31. The light socket terminal 32 is connected by a wire 72 to the contact 53. The contact 54 is connected by a wire 73 to the terminal 25 of the foot plate 19 and the contact 55 is connected by a wire 74 to the terminal 24 of the foot plate 18 and the contact 56 is connected by a wire 75 to the terminal 27 of the heel plate 21.

The contact 58 is connected by a wire 77 to the terminal 26 of the heel plate 20 and the con- 55

tact 59 is connected by a wire 78 to the terminal 27 of the heel plate 21 and the contact 60 is connected by a wire 79 to the terminal 24 of the foot plate 18.

5 In operation when it is desired to have electric current flow through each foot the operator moves the switch block 64 to the right as shown in Fig. 3 and turns the rheostat to the low position and connects the plug 67 with a suitable 10 source of electrical energy. The operator or the person whose feet are to be treated then places his bare feet on the plates 18, 19, 20 and 21 in a position so that the heel of one foot rests on the plate 20 and the heel of the other foot rests on the plate 21. The operator then turns the rheostat 15 up until the desired amount of current is passing through the feet.

When the switch block 64 is in the position shown in Fig. 3 the electrical current passes from 20 the negative wire 68, through the fuse 52 to the rheostat coil 39, through the contact arm 43 to the contact track 41 and thence through the wire 71 to the terminal 31 of the lamp socket and through the bulb 29 to the terminal 32. From 25 the lamp socket terminal 32 the current flows through the wire 72 to the contact 54 and thence through the contact bar 61 to the contacts 54 and 55. From the contact 54 the current flows to the plate 19 and thence through one foot of the person 30 being treated to the heel plate 21 from which it passes through the wire 78 to the contact 59. From the contact 59 the current flows through the contact bar 62 to the contact 57 and thence 35 through the negative wire 69 back to the source of supply.

From the contact 55 the current flows to the plate 18 and thence through the other foot of the person being treated to the heel plate 20 from which it passes through the wire 71 to the contact 40 58 and then through the contact bar 62 to the contact 57 from which it returns to the source of supply through the negative wire 69. From the foregoing it will be apparent that a flow of 45 electricity is directed through each foot of the person being treated. This flow of current through the feet stimulates the circulation of blood in the feet and strengthens the arch muscles of the feet.

For treating a person's ankles to strengthen the 50 muscles thereof it is desirable to direct the flow of electricity in one foot, through the person's body and out through the other foot.

When it is desired to treat the ankles a person's feet engage the plates 18, 19, 20 and 21 in 55 the same manner as previously described, but the switch bar 64 is moved to the left in which position the contact bar 61 bridges the positive contacts 53, 54 and 56 and the contact bar 62 bridges the negative contacts 57, 58 and 60. 60 When the switch 38 is in this position the current flows from the positive contact 53 through the contact bar 61 to the contact 54 and thence

through the wire 73 to the plate 19 the same as previously described, but instead of the heel plates 21 being connected to the negative side of the line it is connected by the wire 76 to the positive side of the line thereby making both the plate 19 and the plate 21 positive. Thus the current passes into the right foot of the person being treated, through his body to the left foot and thence through the plate 18 to the wire 79 to the contact 60 and through the contact bar 62 to the contact 58 from which it returns to the source of supply through the negative wire 69. At the same time some of the current passes through the heel plate 20 and the wire 77 to the contact 58 and through the contact bar 62 to the contact 57.

From the foregoing description it will be apparent that I have provided a novel therapeutic device which is simple in construction and highly efficient in use.

Having thus described my invention, I claim:

1. In a therapeutic device, a base made of insulating material, a pair of toe plates secured to said base, a pair of heel plates secured to said base, said heel plates and toe plates being made of electrical conducting material and being arranged in adjoining pairs with the heel plates spaced from the toe plates, said base having a cavity therein, a switch disposed in said cavity, said switch including a last named base, said base having four pairs of opposed contact members thereon, a circuit closing member adapted in one position to bridge three pairs of contact members and a plurality of leads connecting said contact members to said heel plates and to said toe plates in such fashion that when the circuit closing member is in one position it will cause current to flow from each heel plate to each toe plate when the same are connected and whereby when the circuit closing member is in another position it will cause current to flow from one pair of adjacent toe and heel plates to the other adjacent toe and heel plates when they are connected.

2. In a therapeutic device, a source of electrical energy, a base of insulating material, a pair of toe contact plates, a pair of heel contact plates, said pairs of contact plates being mounted in fixed spaced relation on said base, a switch mounted on said base, said switch including a plurality of fixed terminals and a movable member cooperating with said terminals, and leads from said switch terminals to said plates, whereby in one position of said movable switch member the plates will be energized to cause a potential difference between each toe plate and its adjacent heel plate, and in another position of said movable switch member the plates will be energized to cause a potential difference between the toe plates and between the heel plates.

LEONARD F. RUCKER.
